Primary Examiner — W. A. Teddy Falloway*Assistant Examiner* — Melissa A Santos*(74) Attorney, Agent, or Firm* — Jose Cherson Weissbrot(57) **CLAIM**

The ornamental design for a LED solar strip light, as shown and described.

DESCRIPTION

FIG. 1 is a first perspective view of a LED solar strip light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1; and,

FIG. 11 is an enlarged view of the selected portion 11 in FIG. 2.

The broken lines shown in the drawings depict portions of the LED solar strip light that form no part of the claimed design.
